UNITED STATES PATENT OFFICE.

HORACE E. MILLER, OF NEWARK, NEW JERSEY, ASSIGNOR TO THE CELLULOID COMPANY, OF NEW YORK, N. Y., A CORPORATION OF NEW JERSEY.

DESIGN FOR A MIRROR-FRAME, &c.

SPECIFICATION forming part of Design No. 30,393, dated March 28, 1899.

Application filed September 30, 1897. Serial No. 653,647. Term of patent 7 years.

To all whom it may concern:

Be it known that I, HORACE E. MILLER, a citizen of the United States, residing at Newark, county of Essex, and State of New Jersey, have invented and produced a certain new and original Design for Mirror-Frames and the Like, of which the following is a specification.

My invention is illustrated in the accompanying drawings, forming part of this specification, of which the leading characteristic and essential feature is the circular and re-entrant roll given to the extreme outer periphery of the frame.

In the drawings forming part of this specification, Figure 1 is a front elevation, and Fig. 2 a central sectional elevation thereof.

At 1 in the drawings is the backing, which is shown as circular in form and which projects outwardly, as shown in Fig. 2, partak-

ing of a convex or dish-shaped appearance or configuration.

At 2 is the rim, which comprises the outward roll 3, segmental in form and merging into the back 1, and a reentrant inward roll 4, segmental in form and merging into the outer roll 3, the free edge 5 of the inner roll approaching close to the inner surface of the outer roll 3, the inner circular face 6 of which is presented toward the backing 1. 30 25

Having described my invention, I claim—
The design for a mirror-frame or the like, substantially as described and shown.

Signed at the city of Newark, county of Essex, and State of New Jersey, this 16th day of September, 1897. 35

HORACE E. MILLER.
